US0D1034977S

(12) **United States Design Patent** (10) Patent No.: **US D1,034,977 S**
(45) Date of Patent: ** Jul. 9, 2024

(54) CONTROL HANDLE GRIP FOR A CATHETER	3,773,034 A	11/1973	Burns et al.	
(71) Applicant: IPG Photonics Corporation , Oxford, MA (US)	D230,927 S *	3/1974	Goletski et al.	D8/303
(72) Inventors: Gregory Altshuler , Lincoln, MA (US); Ilya Yaroslavsky , N. Andover, MA (US); Dmitri Boutousov , Southborough, MA (US); Viktoriya Andreeva , Mytishchi (RU); Olivier Traxer , Paris (FR); Michael Barenboym , Boston, MA (US); Isaac Ostrovsky , Wellesley, MA (US); Anastasiya Kovalenko , Mytishchi (RU); Jeffrey Michael Treen , Nashua, NH (US)	4,700,693 A	10/1987	Lia et al.	
(73) Assignee: IPG Photonics Corporation , Oxford, MA (US)	D313,849 S	1/1991	Robinson	
(**) Term: 15 Years	D318,733 S	7/1991	Wyzgala	
(21) Appl. No.: 29/800,841	D318,734 S	7/1991	Wyzgala	
(22) Filed: Jul. 23, 2021	D326,154 S	5/1992	Deguchi et al.	
(51) LOC (14) Cl. 24-02	D326,714 S	6/1992	Funakoshi et al.
